(57) **CLAIM**

The ornamental design for a freezer shroud, as shown and described.

DESCRIPTION

FIG. 1 is a perspective view of the freezer shroud;
FIG. 2 is a front elevational view of the freezer shroud;
FIG. 3 is a rear elevational view of the freezer shroud;
FIG. 4 is a left side elevational view of the freezer shroud;
FIG. 5 is a right side elevational view of the freezer shroud;
FIG. 6 is a top plan view of the freezer shroud; and,
FIG. 7 is a bottom plan view of the freezer shroud.
The broken lines shown in the drawings are for illustrative purposes only and form no part of the claimed design.
